G. J. Woods,

UNITED STATES PATENT OFFICE.

GRANVILLE T. WOODS, OF NEW YORK, N. Y., ASSIGNOR TO GENERAL ELECTRIC COMPANY, A CORPORATION OF NEW YORK.

ELECTRIC-RAILWAY APPARATUS.

SPECIFICATION forming part of Letters Patent No. 762,792, dated June 14, 1904.

Application filed October 12, 1901. Serial No. 78,513. (No model.)

To all whom it may concern:

Be it known that I, GRANVILLE T. Woods, a citizen of the United States, and a resident of New York, in the county of New York and State of New York, have invented certain new and useful Improvements in Electric-Railway Apparatus, of which the following is a specification.

My present invention relates to improvements in electric railways of the surface-contact or sectional-conductor type, and has for its object to produce an efficient, safe, and reliable system in which a series of normally dead sectional electrical conductors are automatically connected to a feeder of electrical energy.

My invention consists of improvements in the construction and arrangement of the parts of the system with especial reference to the electromagnetically-actuated circuit-controlling devices for connecting the feeder with the sections of the sectional conductor, as will be hereinafter more fully explained, and clearly set forth in the appended claims.

In the accompanying drawings, which illustrate the preferred embodiment of my invention, Figure 1 is a diagrammatic view of the improved system including one arrangement of the car apparatus. Fig. 2 is a side view of a detail of the clutch mechanism used in connection with the driving mechanism for the generator or auxiliary source of power carried by the car.

Referring now to the drawings, B represents the main generator supplying current to the system through the main feeder K.

At C is a motor-generator, the motor 1 of which is connected to the main generator B and the generator 2 of which is connected to the auxiliary feeder or low-voltage-supply main L. The motor-generator C is adapted to transform the relatively high-voltage energy received from the generator B into a relatively low voltage.

On most electrical railways where a number of cars are started at the same time the main-line voltage is greatly reduced, and when electromagnetically-controlled switches are used to connect the working conductor with

the feeder and a series coil is employed for the purpose of holding said switches closed the fall in potential is liable to permit the switches to open. Therefore I employ a separate and independent maintaining-circuit for the hold-up coil and supply said maintaining-circuit with a relatively low voltage from the motor-generator C.

The electromagnetically-actuated switches or circuit-controlling devices which are adapted to connect the sections E E' of the sectional conductor to the main feeder K are indicated at D D'. The sections E E' are successively and automatically cut into circuit as the car or vehicle moves over the roadway.

F indicates the grounded return-track rail on which runs the car-wheel G, which is electrically connected to the generator 9 10 and is adapted to be connected in the car-motor circuit. The car-motor H is under control of the controlling-switch I and the reversing-switch J and is supplied with current from the main feeder K through the switches D D', sectional conductor E E', and trolley or collector shoe 13 in a manner to be herein-after described. The auxiliary source of power or current supply which is used for the purpose of initially picking up the electromagnetically-actuated switches comprises the generator 9 10, which is operated by the treadle or foot-lever 3 through the ratchet-and-pawl or clutch mechanism A.

Each electromagnetically-actuated circuit-controlling device comprises a main switch which is operated by the actuating or pick-up coil 15, connected in the actuating-circuit, and is maintained in its closed position by means of the hold-up coil 39, connected in the maintaining-circuit. The maintaining-circuit is supplied with current at a low potential from the auxiliary feeder L through the contacts 36 and 37, which are controlled by current supplied from the main feeder through the coil of the series magnet 31. The contacts 17 and 18 comprise an auxiliary switch which is adapted to open the actuating-circuit when the main switch is closed and is controlled by the magnet 40, the coil of which is connected in the maintaining-circuit and is supplied with

current at a low voltage from the auxiliary conductor L.

The operation of the system is as follows: Current from the main generator B is supplied at a relatively high potential to the main feeder K and also to the motor 1 of the motor-generator C, and the generator 2 supplies current at a low potential to the auxiliary main or feeder L. To initially close the switches, current is supplied to the actuating-circuit from the generator 9 10, carried by the car. If foot-pressure is suddenly applied to the treadle or lever 3, of metal or other conducting material, the energy will be communicated through the connecting-rod 4 to the crank-shaft 5, thereby rotating the wheel or disk 6, which is secured upon said crank-shaft. The movement of the wheel 6 is transmitted to the ratchet-wheel 8 by means of the pawl or dog 7, pivotally mounted on the wheel 6. The armature 9, which is directly connected with the ratchet-wheel 8, is thereby rotated in the field 10, and the current generated passes through the initial pick-up circuit, which may be traced as follows: through the conductor 34, contacts 11 and 12, and bridging-lever 3, conductor 33, shoe 13, conductor-section E, conductor 14, pick-up coil 15, conductor 16, contacts 17 and 18, conductor 19 and 20 to ground at 21. The other side of the generator 9 10 is grounded through the controlling-resistance 25, conductor 24, wheel G, and return-track rail F.

The energization of the actuating-circuit causes the core 22 to be drawn up, and during such movement the core compresses the spring 50, which then acts as a cushion and lifts the lever 26, thereby causing the bridging member 27 of the main switch to bridge the contacts 28 and 29. Upon the closing of said main switch a circuit is completed from the main feeder K through the contacts 27, 28, and 29 of the main switch, conductor 30, actuating-coil of the series magnet 31, conductor 32 to the conductor-section E, and from thence through the collector-shoe 13, conductor 33, contacts 12 and 11, and bridging-lever 3, conductor 34, armature and field 9 and 10, resistance 25, conductor 24, wheel G, return-rail F to ground.

The energization of the series magnet 31 will cause the armature-lever 35 to be operated against the action of the spring 49 to close the maintaining-circuit at the contacts 36 and 37. A low-voltage current will then flow from the auxiliary feeder L through conductor 38, contacts 36 and 37, hold-up coil 39, coil of the circuit-breaking magnet 40, conductors 41 and 20 to ground at 21, it being understood that the other side of the generator 2 is grounded at 42. The completion of said maintaining-circuit causes the energization of the magnet 40, which attracts its armature 43, thereby opening the actuating-circuit at the contacts 17 and 18 and cutting the

pick-up coil 15 out of circuit. It will of course be understood that when the lever 26 is lifted the operating-arm 44 is moved toward the right, thereby removing the pressure of the spring 45 from the lower arm or lever 43, so that the latter lever is free to act when the magnet 40 is energized.

Now if the controlling-switch I is moved so as to complete the motor-circuit through the resistance 25 current will flow from the 75 energized conductor-section E through shoe 13 and thence through the reversing-switch J, the motor H, controlling-switch I, resistance 25, conductor 24, wheel G, return-rail F to ground.

After the controlling-switch has been moved to complete the circuit through the motor H the foot of the motorman may be removed from the lever 3, so as to permit said lever to move to open the initial pick-up circuit at the contacts 11 and 12. This movement of the treadle or foot-lever 3 to cut the auxiliary source of power out of circuit is caused by overbalancing the wheel 6, the weight or lug 46 being formed on said wheel, 90 so as to throw it out of balance and cause it to normally assume the position shown in Fig. 1.

Suppose that the car is moving from left to right. Then as soon as the collector-shoe 13 makes an electrical connection with the section E' of the sectional conductor a part of the main power-current will be shunted from the motors into the said section E' through the shoe 13. The actuating-circuit, including the pick-up coil 15 and contacts 17 and 18 of the advance switch D', will therefore be energized. The core 22 of said switch will then be lifted, and the section E' will be connected to the main feeder K through the contacts 28 and 29, bridged by the bridging contact member 27. As before described with reference to switch mechanism D, upon the completion of the connection between the feeder K and section of the sectional conductor the series magnet 31 will be energized to cause the maintaining-circuit through the hold-up coil 39 to be completed at the contacts 36 and 37, and after said maintaining-circuit has been completed the circuit-breaking magnet 40 will cause the actuating-circuit to be broken at the contacts 110 17 and 18. A further movement of the shoe 13 sufficient to cause it to leave the sectional conductor E will deprive the coil 31 of the switch mechanism D of its energy. Then the spring 49 will move lever 35 so as to open the maintaining-circuit at the contacts 36 and 37 and deprive the hold-up coil 39 of energy, thereby allowing the core 22 to begin a rapid descent.

The tension of spring 49 may be adjusted by means of screw 52. The downward movement of said core is assisted by the spring 50, which presses against the strap 51, and the core 22 impinges the lever 26 in such a manner as to prevent the contact 27 from sticking to contacts 28 and 29. The spring 120 130

45 now engages the lower arm of the lever 43, thereby causing the contacts 17 and 18 to be brought into engagement with each other, thus leaving the section E prepared for action in case a car approaches that section. The direction of the car movement will make no difference in the action of the electromagnetic pick-up apparatus.

Another reason for employing currents of 10 different voltages is as follows: In systems in which it is desired that the hold-up coil, such as coil 39, be maintained in the circuit in shunt to the motor or motors carried by the car a large amount of costly and very fine wire 15 must be used; but by employing a low-voltage current in the hold-up coil much less expensive wire will be required to accomplish the desired result.

If occasion should require it, current from 20 K may be fed to the pick-up apparatus by shifting a switch, such as 54, so as to cut the resistance 55 into the circuit between the feeder K and the maintaining-circuit. When large currents are drawn to feed the driving- 25 motor H, a shunt around the coil of the series magnet 31 may be employed in such a manner as shown at 56 in switch apparatus D'. By the use of such a shunt the coil of magnet 31 will not have to be made unduly large. The 30 switch 57 may be employed to complete a shunt-circuit around the contacts 28 and 29 in case of trouble with the circuits in the pick-up apparatus. The lamps at 58 may be cut into the circuit by means of the switch 35 59. The circuit which includes said lamps at 59 may be termed a "coasting-circuit," because when such circuit is closed sufficient current will flow through the coil of magnet 31 to maintain an electrical connection between the feeder K and the sectional conductor. 40

What I claim as new, and desire to secure by Letters Patent of the United States, is—
1. In combination, a plurality of circuits 45 adapted to convey electrical energy, a set of four coils arranged in connection with said circuits, and a plurality of switches adapted to act in sequence in obedience to the energy received by such coils so that the first coil 50 receiving energy controls the circuit of the second coil, the second coil then controls the circuit through the third and fourth coils, the third coil then sustains the act of the first coil and the fourth coil controls the circuit of the first coil.

2. In an electric railway, the combination 55 with the source of electrical energy, of a car-driving motor, a normally dead sectional work-conductor, electromagnetic devices adapted to connect and disconnect the sections of said sectional conductor to and from said source of energy, each of said electromagnetic devices having four coils and three switches, one of said coils being adapted to initially actuate one of said switches, another of said coils be-

ing arranged to maintain said switch in the position to which the first coil moved it, a third one of said coils controlling the second switch to govern the circuit of said second coil, and the remaining coil and switch being 70 adapted to control the circuit of said initially-actuating coil.

3. In an electric railway, the combination with a feeder, of a single series of normally dead work-conductor sections, an electromagnetically-actuated primary switch for each of said work-conductor sections, a connection from each of said sections to ground or return main including an initially-actuating coil for moving said primary switch, a switch for controlling said return connection through said initially-actuating coil, a circuit-breaking coil adapted to open the latter switch and break said return connection, a holding-coil in circuit with said circuit-breaking coil and adapted 75 to hold said primary switch closed, a circuit-controlling switch for the circuit of said holding-coil, and a coil in series with the car-driving motor and adapted to control the latter switch.

4. In an electric railway, the combination of the main feeder, an auxiliary feeder, a return-conductor, a car-driving motor in electrical communication between said main feeder and said return-conductor, and an electromagnetic device in circuit with said motor and adapted to control the circuit connections from said feeder to said motor, the said electromagnetic device including four coils, the initially-acting coil being in shunt to said motor, another coil being in series with said motor, the remaining coils being in series with each other and receiving a low-voltage current from said auxiliary feeder, the two former coils being energized by a high-voltage 90 current from the power-circuit.

5. In a sectional-conductor railway system, a main circuit, a circuit-controlling device having switch-contacts adapted to control said main circuit, an initially-operating circuit 100 adapted to receive energy from said main circuit and containing contacts adapted to connect said operating-circuit to said main circuit, and an auxiliary circuit having contacts adapted to convey energy to maintain the 105 action of said operating-circuit.

6. In a sectional-conductor railway system, a circuit-controlling device having switch-contacts to control a main circuit, an actuating-coil to govern said contacts, switch-contacts to control an auxiliary circuit, an actuating-coil to govern the latter contacts, switch-contacts to control an initially-operating circuit, and an actuating-coil to govern the latter contacts.

7. In a railway system, the combination of a single sectional conductor, a main feeder, an auxiliary feeder, and a circuit-controlling device provided with four coils and three switches, one of said coils being connected in 125 130

- circuit with one of said switches and between one section of said sectional conductor and the ground, another one of said coils being adapted to be connected in circuit with another of said 5 switches and between the said conductor-section and the main feeder, and the remaining two of said coils and the remaining switch being adapted to be connected in series between said auxiliary feeder and the ground.
10. 8. In an electric railway, a main or power circuit, an auxiliary or low-voltage circuit, a single sectional work-conductor, and an electromagnetic circuit-controlling device arranged between said power-circuit and a section 15 of said work-conductor and adapted to be connected in both of said circuits, said circuit-controlling device including four coils and three switches, the initially-acting coil having one of its terminals permanently connected to
- 20 a conductor-section and its other terminal normally connected through one of said switches to ground, two of the remaining coils being in series with each other and having one terminal permanently connected to ground and the other terminal connected through another one of said switches to said auxiliary circuit, the remaining coil having one of its terminals arranged to be connected through the remaining switch to said power-circuit and its other 25 terminal permanently connected to the conductor-section to which said initially-acting coil is connected.
9. In a railway system of the character described, a car, normally dead conductor-sections arranged along the railway, feeder-circuits for the system, a circuit-controlling device adapted to connect one of said conductor-sections to said feeder-circuits, a generator carried by said car and adapted to initially 30 actuate said circuit-controlling device, a clutch mechanism whereby said generator may be set in motion, and means adapted to close and open the circuit of said generator.
10. In an electric railway of the character described, the combination of the main or power circuit, the auxiliary circuit, the sectional work-conductor, switches for connecting the sections of the latter conductor to said power-circuit, means for actuating said 45 switches, and means for connecting said auxiliary circuit so as to supply energy to maintain said switches.
11. In an electric-railway system, a circuit-controlling device provided with three switches which are so constructed and arranged that the switch which is the second one to close will be the first one to open, and the switch which is the first one to close will be the second one to open, and the opening of the 55 latter switch will cause the third switch to close.
12. In a sectional-conductor electric-railway system, the combination of a car, normally dead conductor-sections arranged along 60 the roadway, feeder-circuits for the system, a circuit-controlling device adapted to connect one of said conductor-sections to said feeder-circuits, a generator carried by said car and adapted to generate current to initially actuate said circuit-controlling device, mechanical 70 means whereby said generator may be actuated by an initial impetus only, and a switch operatively related to said mechanical means for controlling the circuit of said generator.
13. In a sectional-conductor electric rail-way, a main source of power, a main feeder, an auxiliary feeder, a sectional conductor, an auxiliary source of power, switches for connecting said sectional conductor to said main feeder, means for operating said switches from 80 said auxiliary source of power, and means for maintaining said switches by current from said auxiliary feeder after they have been operated.
14. In a sectional-conductor electric rail-way, a main source of power, a main feeder, an auxiliary feeder, a sectional conductor, an auxiliary source of power, switches for connecting said sectional conductor to said main feeder, means for operating said switches from 85 said auxiliary source of power, means for maintaining said switches by current from said auxiliary feeder after they have been operated, and means for cutting off the supply of current from the auxiliary source of power 90 without affecting said maintaining means.
15. In a sectional-conductor electric rail-way, a main source of power, a main feeder, an auxiliary feeder, a sectional conductor, an auxiliary source of power, switches for connecting said sectional conductor to said main feeder, means for operating said switches from 95 said auxiliary source of power, means for maintaining said switches by current from said auxiliary feeder after they have been operated, and means for cutting off the supply of current from the auxiliary source of power without affecting said maintaining means.
16. In a sectional-conductor electric rail-way, a main source of power, a main feeder, an auxiliary feeder, a sectional conductor, an auxiliary source of power, switches for connecting said sectional conductor to said main feeder, means for operating said switches from 100 said auxiliary source of power, means for maintaining said switches by current from said auxiliary feeder after they have been operated, means for cutting off the supply of current from the auxiliary source of power without affecting said maintaining means, and means for cutting off the supply of current from the auxiliary feeder to permit the 105 switches to open.
17. In a sectional-conductor electric rail-way, a main source of power, a main feeder, an auxiliary feeder, a sectional conductor, an auxiliary source of power, switches for connecting said sectional conductor to said main feeder, means for operating said switches from 110 said auxiliary source of power, means for maintaining said switches by current from said auxiliary feeder after they have been operated, means for cutting off the supply of current from the auxiliary source of power without affecting said maintaining means, and means operated by the current from the main feeder for controlling the supply of current 115 from the auxiliary feeder to the maintaining means.
18. In a sectional-conductor electric rail-way, a main feeder, an auxiliary feeder, a sectional conductor, electromagnetic switches for 120
19. In a sectional-conductor electric rail-way, a main feeder, an auxiliary feeder, a sectional conductor, electromagnetic switches for 125
20. In a sectional-conductor electric rail-way, a main feeder, an auxiliary feeder, a sectional conductor, electromagnetic switches for 130

- connecting the sections of said sectional conductor to said main feeder, an actuating-circuit and a maintaining-circuit for each switch, means for connecting each actuating-circuit 5 to a suitable source of power to close said switches, and means for connecting each maintaining-circuit to said auxiliary feeder to maintain said switches in their closed position.
18. In a sectional-conductor electric rail-way, a main feeder, an auxiliary feeder, a sectional conductor, electromagnetic switches for connecting the sections of said sectional conductor to said main feeder, an actuating-circuit and a maintaining-circuit for each switch, 10 means for connecting said actuating-circuit to a suitable source of power to close said switches, means for connecting each maintaining-circuit to said auxiliary feeder to maintain said switches in their closed position, and 15 means controlled by said electromagnetic switches and operated by current from the main feeder for connecting the maintaining-circuit to the auxiliary feeder after the switch has closed.
19. In a sectional-conductor electric rail-way, a main feeder, an auxiliary feeder, a sectional conductor, electromagnetic switches for connecting the sections of said sectional conductor to said main feeder, an actuating-circuit 20 and a maintaining-circuit for each switch, means for connecting each actuating-circuit to a suitable source of power to close said

switches, means for connecting each maintaining-circuit to said auxiliary feeder to maintain said switches in their closed position, 35 means controlled by said electromagnetic switches and operated by current from the main feeder for connecting the maintaining-circuit to the auxiliary feeder after the switch has closed, and means for disconnecting said 40 actuating-circuit from said source of power without affecting the connections of said maintaining-circuit.

20. In a sectional-conductor electric rail-way, a main feeder, an auxiliary feeder, a sectional conductor, connections between the sections of said sectional conductor and said main feeder, switches in said connections, an actuating-coil and a maintaining-coil for each of said switches, means for connecting said actuating-coil normally in a circuit from a conductor-section to the return, means actuated 45 by current from the main feeder for completing the circuit from said auxiliary feeder to the maintaining-coil, and means for opening 50 the circuit through the actuating-coil after the maintaining-coil has been energized.

Signed at New York, in the county of New York and State of New York, this 25th day of July, A. D. 1898.
